N. J. KNAPP.
LOCOMOTIVE LAMP.

No. 25,421.

Patented Sept. 13, 1859.

UNITED STATES PATENT OFFICE.

NELSON J. KNAPP, OF CHICAGO, ILLINOIS.

IMPROVEMENT IN LOCOMOTIVE-LAMPS.

Specification forming part of Letters Patent No. 25,421, dated September 13, 1859.

To all whom it may concern.

Be it known that I, NELSON J. KNAPP, of Chicago, in the county of Cook and State of Illinois, have invented a new and Improved Lamp for Locomotives, Ships, &c.; and I do hereby declare that the following is a full, clear, and exact description of the same, reference being had to the accompanying drawings, making a part of this specification, in which—

Figure 1 is a longitudinal vertical section of my invention, taken in the line $x-x$ of Fig. 2. Fig. 2 is a transverse vertical section of the same in the line $y-y$ of Fig. 1.

Similar letters of reference indicate corresponding parts in the two figures.

This invention consists in combining an ellipsoidal and a paraboloidal reflector, as hereinafter fully shown and described, whereby I am enabled to use a large flame and have the rays of light which issue therefrom projected parallelly within the limited dimensions required, in order to receive the full benefit thereof.

In locomotive-lamps, commonly termed "head-lamps," which are placed on the front part of the locomotive, in order to throw light on the track, a paraboloidal reflector is used, in order that the reflected rays may be projected parallelly, and, so far as possible, kept within a space equal in width to the track. In order, however, to carry out this plan, the flame of the lamp is necessarily placed at the focus of a paraboloid, and as the focus of a paraboloid of sufficient dimensions to keep the rays of light within a compass equal to the width of the track is quite near the back end of the paraboloid a flame of quite limited size can only be used.

By my invention, as previously stated, I am enabled to use a large flame and throw a more brilliant and intense light on the track at a greater distance than usual. The invention is applicable to ships, and also may be used for signal-lights, &c.

To enable those skilled in the art to fully understand and construct my invention, I will proceed to describe it.

A represents the case of a lamp, which may be constructed of sheet metal, and B

represents a slide, which is fitted in the bottom of the back part of the case and allowed to slide transversely in and out from the case. To this side B the usual Argand burner C and fountain D are attached.

E is an ellipsoidal reflector, which is placed within the case A. One half a of this reflector is attached to the slide B, and the burner C is placed within it at its focus b . The other half c is secured permanently within the case and has a paraboloidal reflector D attached to its outer end. The part c of the ellipsoidal reflector E and the paraboloidal reflector D have a common focus d , as shown clearly in Fig. 1. The reflectors E D may be constructed of any of the materials used for such purpose, and the outer end of the reflector D is covered by a glass F and is flush with the end of the case A, as shown clearly in Fig. 1.

From the above description of parts it will be seen that all the rays of light from the flaine e , which is at the focus b , that are reflected from the ellipsoid E will pass through the other focus d of the ellipsoid, and as the focus d is common to both the ellipsoid E and paraboloid D the rays reflected from E and cast against the inner side of D will be reflected therefrom in parallel rays, as shown in Fig. 1. The features of the ellipsoid and paraboloid are well known, and therefore do not require any particular elucidation.

The foci of the ellipsoid E are at some distance from its ends; but the focus of the paraboloid is quite near its end, and consequently with a small paraboloidal reflector alone a comparatively small burner could only be used. By referring to Fig. 1 this will at once be seen. By my invention, therefore, I am enabled to use a comparatively large burner with a medium-sized paraboloid, and thereby concentrate its rays of light to a greater degree than usual and project them farther into space. If a paraboloid were made sufficiently larger than D to receive the burner C at its focus d , said paraboloid would not, on account of its increased diameter, concentrate the rays like D, and consequently their intensity would be comparatively diminished.

This invention will prove highly valuable for locomotive and ship-lamps, and will be also valuable for signal-lamps.

What I claim as new, and desire to secure by Letters Patent, is—

The combination of the ellipsoidal and paraboloidal reflectors E D and burners C, ar-

ranged substantially as and for the purpose set forth.

NELSON J. KNAPP.
